UNITED STATES PATENT OFFICE.

LEON LUKACHER, OF CHICAGO, ILLINOIS.

COIN-HOLDER.

1,289,840.

Specification of Letters Patent. Patented Dec. 31, 1918.

Application filed October 13, 1916. Serial No. 125,496.

To all whom it may concern:

Be it known that I, LEON LUKACHER, a citizen of the United States, and a resident of the city of Chicago, county of Cook, and 5 State of Illinois, have invented certain new and useful Improvements in Coin-Holders, of which the following is a specification.

My invention relates to improvements in coin holders especially adapted for use in 10 wrapping coins, and has for its object the provision of an improved construction of this character which is simple and efficient in operation and capable of economical manufacture.

15 The invention consists in the combinations and arrangements of parts hereinafter described and claimed.

The invention will be best understood by 20 reference to the accompanying drawings forming a part of this specification, and in which,

Figure 1 is a side view of a coin holder embodying my invention,

Fig. 2, a view of the opposite side of the 25 holder shown partially in section,

Fig. 3, a top plan view of the holder,

Fig. 4, a top plan view of the base of the holder showing a portion of the body thereof in horizontal section,

30 Fig. 5, an enlarged detail section taken on line 5—5 of Fig. 4, and

Fig. 6, a view of a pair of tongs employed in conjunction with the construction.

The preferred form of construction, as 35 illustrated in the drawings, comprises a suitable base or support 7 having a notch 8 in one edge thereof. The support 7 is provided with a central spindle 9 in the form of a removable bolt and a coin holding block 10 is rotatably mounted on the spindle 9. Both 40 the block 10 and the base 7 are preferably made of wood, and the block 10 is provided with a plurality of vertical openings 11, 12, 13, 14 and 15, extending therethrough

45 and adapted respectively to receive and hold pennies, nickels, dimes, quarters and half dollars. Each of said openings is provided in its outer side with a slot 16, as indicated, and the sides of said slots are provided with 50 graduations adapted to indicate the number of coins in the respective openings. The block 10 is provided with a spring-held plunger or pin 17 and the top of the base 7 is provided with a metallic plate 18 having 55 a plurality of openings 18' therein pos-

tioned on the same radius as the pin 17 and located angularly to receive said pin when any one of the slots 16 is in registration with the notch 8, the end of the pin 17 being rounded as indicated, to yieldingly hold the 60 block 10 in such position to permit of ready re-adjustments thereof. A handle 19 is provided on the top of block 10 to facilitate rotations thereof. By this arrangement, it will be observed that the different coin-receiving openings 11, 12, 13, 14 and 15 may be readily rotated to bring their corresponding slots 16 in registration with the notch 8, as desired.

A combined guide and guard member 20 70 is mounted to oscillate upon the spindle 9 and extends over the top of the block 10, being provided with depending flanges or guard members 21 and 22, the guard member 21 being adapted to be positioned immediately outside of each of the slots 16 for the openings 11, 12 and 13, and the guard member 22 being similarly adapted to be positioned immediately outside of each of the slots 16 for the openings 14 and 15. The 75 member 20 is provided with openings 23 and 24, the opening 23 being adapted to register with openings 11, 12 and 13, and the opening 24 to register with openings 14 and 15, the opening 23 being of a size to 80 permit the passage of nickels, dimes and pennies, and the opening 24 being of a size to permit of the passage of half dollars and quarters. The openings 23 and 24 are provided with upwardly extending substantially funnel-shaped guide members 25 and 26 adapted to facilitate the entry of coins to the respective openings. By this arrangement, it will be observed, that the coins may be readily placed in the respective openings 90 by swinging the proper opening 23 or 24 into registration therewith, the corresponding guide member 21 or 22 being at the same time positioned to prevent egress of 95 coins from the corresponding slot 16.

I also provide a suitable pair of tongs 27 having upwardly turned ends 28 for removing the coins from the openings 11, 12, 13, 14 and 15. In use, the tongs are engaged with the bottom and top of a stack 105 of coins in the coin-receiving opening in registration with notch 8, said notch permitting of such engagement and then the stack of coins is removed by elevating the tongs, the corresponding slot 16 permitting 110

of such elevation. The coins in the tongs may then be readily wrapped with a suitable wrapper, as will be readily understood.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A coin holder comprising a base; and a coin holding member rotatable on said base and having a plurality of openings extending therethrough for the reception of coins, there being slots in the outer sides of said openings and a notch in said base extending inwardly to the centers of said openings and arranged to register with said slots, substantially as described.

2. A coin holder comprising a base; a coin holding member rotatable on said base and having a plurality of openings extending therethrough for the reception of coins, there being slots in the outer sides of said openings and a notch in said base extending inwardly to the centers of said openings and arranged to register with said slots; and graduations on the sides of said slots indicating the contents thereof, substantially as described.

3. A coin holder comprising a base; a coin holding member rotatable on said base and having a plurality of openings extending therethrough for the reception of coins, there being slots in the outer sides of said openings and a notch in said base extending inwardly to the centers of said openings and arranged to register with said slots; and yieldable means for positioning said member on said base with any one of said slots in registration with said notch, substantially as described.

4. A coin holder comprising a base; a coin holding member rotatable on said base and having a plurality of openings extending therethrough for the reception of coins, there being slots in the outer sides of said openings and a notch in said base extending inwardly to the centers of said openings and arranged to register with said slots; graduations on the sides of said slots indicating the contents thereof; and yieldable means for positioning said member on said base

with any one of said slots in registration with said notch, substantially as described.

5. A coin holder comprising a base; a coin holding member rotatable on said base and having a plurality of openings extending therethrough for the reception of coins, there being slots in the outer sides of said openings and a notch in said base extending inwardly to the centers of said openings and arranged to register with said slots; and a combined guide and guard arranged to guide coins into said openings and prevent egress of coins from said slots, substantially as described.

6. A coin holder comprising a base; a coin holding member rotatable on said base and having a plurality of openings extending therethrough for the reception of coins, there being slots in the outer sides of said openings and a notch in said base extending inwardly to the centers of said openings and arranged to register with said slots; graduations on the sides of said slots indicating the contents thereof; yieldable means for positioning said member on said base with any one of said slots in registration with said notch; and a combined guide and guard arranged to guide coins into said openings and prevent egress of coins from said slots, substantially as described.

7. A coin holder comprising a base having a notch in one edge thereof; a coin block rotatably mounted on said base and having coin receiving openings extending vertically therethrough, there being slots in the outer sides of said openings arranged to register with said notch; a spring held locking pin in said block yieldingly contacting with said base; sockets in said base arranged to receive said pin and position said block with the different slots registering with the notch in the base; a combined guide and guard member pivotally mounted on the axis of said block, extending across the top of said block and downwardly over the sides thereof, there being openings in said guide and guard member registering with the upper ends of the openings in the block; and funnel shaped guide members surrounding the openings in said combined guide and guard member, substantially as described.

In testimony whereof I have signed my name to this specification in the presence of two subscribing witnesses.

LEON LUKACHER.
